ABSTRACT: A balanced telephone circuit includes a microphone connected to the input of a transistor amplifier means having two same-phased outputs and a common output. One of the two same-phased outputs is connected to a first wire of a subscriber's line. The telephone receiver is connected across the first wire of the subscriber's line and the other of the same-phased outputs. An artificial load is connected across the other of the same-phased outputs and the second wire of the subscriber's line which is connected to the common output.

BALANCED TELEPHONE INSTRUMENT CIRCUIT

The present invention relates to a balanced telephone instrument circuit of the kind that comprises a microphone, a telephone receiver, an amplifier for the microphone and a subscriber's line.

In such instrument circuits it is common to have a balance transformer for eliminating the influence on the telephone receiver of signals generated in its own microphone. For production technical reasons it is advantageous to be able to do without the balance transformer. According to the present invention this is possible if the instrument circuit is realized in accordance with the characteristics of the following claims.

The invention will be described in greater detail with reference to the accompanying drawing showing a telephone instrument circuit according to the invention.

In the drawing reference M denotes a microphone, reference T₁-T₂-T₃ denotes an amplifier for the microphone M, reference H denotes a telephone receiver, reference R_b-C_b denotes an artificial load and reference L_a-L_b denotes a subscriber's line. The microphone amplifier T₁-T₂-T₃ comprises three transistors T₁, T₂ and T₃ each having one emitter resistor R₂, R₅ and R₆ respectively. The microphone M is connected via resistor R₁ to the base of the transistor T₁ and via a capacitor C₁ and the resistor R₂ to the emitter of the transistor T₁, which emitter is directly connected to the base of the transistor T₂. The connection point between the capacitor C₁ and the microphone M is connected via a resistor R₃ and moreover via a resistor R₄ and a capacitor C₃ connected to one part L_b of the subscriber's line. The emitter of the transistor T₂ is directly connected to the base of the transistor T₃ and is connected to the part L_b of the line via the resistor R₅, while its collector is connected to an output terminal U₁ which is in turn connected to the other part L_a of the subscriber's line. The emitter of the transistor T₃ is connected to the part L_b of the line via the resistor R₆ and its collector is connected to a second output terminal U₂ which is in turn connected to the part L_a of the line via the telephone receiver H. The telephone receiver H and the artificial load R_b-C_b constitute a series connection which via the capacitor C₃ is connected between the parts L_a and L_b of the subscriber's line. The output terminals U₁ and U₂ can be said to constitute two output terminals which, seen from the outside, are independent of each other and which carry signals of the same phase, while a third output terminal U₃ on the microphone amplifier is connected to the part L_b.

The purpose of capacitor C_b, which is in parallel with the resistor R_b, is to imitate the subscriber's line L_a-L_b, which is generally capacitive. This capacitor may be excluded. The balance resistor R_b constitutes the alternating current load of the transistor T₃.

As examples the following values are given for the units shown in the drawing.

R ₁ 300 Ω	R ₃ 100 Ω	C ₁ 10 μF.
R ₂ 0-1000 Ω	R ₄ 100 Ω	C _b 0.15 μF.
R ₅ 100.10 ³ Ω	R ₆ 300 Ω	C ₃ 6 μF.

R₄ 56.10³ Ω

In the amplifier shown as an example the transistor T₁ works as a common amplifier for the output transistors T₂ and T₃. The detailed way of controlling the output transistors T₂ and T₃ can be modified in many ways. The transistors T₂ and T₃ are arranged to emit an alternating current component in their collector current of the same phase. The condition for balance across the telephone receiver is that the product of the current from the terminal U₁ multiplied by the line impedance is equal to the product of the current from the terminal U₂ multiplied by the impedance of the artificial load. In reality this can only be approximately fulfilled because of variations in the line impedance. By suitably choosing the relation between the alternating currents from outputs U₁ and U₂ and by choosing suitable values for resistor R_b and C_b capacitor and for the impedance in the telephone receiver apart from balance a desired instrument impedance, seen from the line, may also be obtained.

The microphone M has a DC resistance of typically less than 600 ohms. The microphone signal is amplified by the transistors T₁ and T₂. The DC bias current of transistor T₁ is supplied by the voltage divided network of resistors R₃ R₄. Part of the amplified signal voltage appears across the resistor R₅ which also provides DC bias to transistor T₃. The function of the resistor R₂ is to limit the amplification of the amplifier comprising transistors T₁ and T₂ by negative feedback. Thus the part of the amplifier in front of transistor T₃ constitutes a conventional signal amplifier. The balance current transistor T₃ receives its bias and signal currents from the emitter of transistor T₂. The resistors R₅ and R₆ being of similar magnitude, the collector current of transistor T₃ contains a signal current of the same phase as that of transistor T₂ and of similar magnitude. Balance, i.e., no signal current through the earphone H, is thus achieved, as explained elsewhere, for a certain ratio of line impedance and balance impedance (C_b, R_b), dependent upon the ratio of transistor collector signal current of the transistors T₁ and T₂ versus the collector signal current of transistor T₃. The earphone H has a typically low DC resistance and the capacitors C₁ and C₃ low impedances for the signal current.

I claim:

1. A balanced telephone instrument circuit for connection to a subscriber line having at least two wires, said circuit comprising: a microphone for generating voice signals; a transistor amplifier means comprising at least two transistors of the same type, each having a collector terminal, an emitter terminal and a base terminal; means for applying the same-phase of signal from said microphone across the base and emitter terminals of said transistors; a common output connected to one wire of said subscriber line; means for connecting the emitter terminals of said transistors to said common output; means for connecting the collector terminal of one of said transistors to the other wire of said subscriber line; a telephone receiver connecting the collector terminal of the other of said transistors to said other wire of said subscriber line; and an artificial load connected between the collector terminal of said other of said transistors and said common output.
